UNITED STATES PATENT OFFICE.

RAPHAEL SERGEANT, OF PITTSBURG, PENNSYLVANIA.

BOLSTER-PLATE.

SPECIFICATION forming part of Letters Patent No. 314,730, dated March 31, 1885.

Application filed July 17, 1884. (No model.)

To all whom it may concern:

Be it known that I, RAPHAEL SERGEANT, of Pittsburg, in the county of Allegheny and State of Pennsylvania, have invented a new and useful Improvement in Bolster-Plates; and I do hereby declare the following to be a full, clear, and exact description thereof.

My improvement in bolster-plates is designed to cheapen the manufacture of the same by doing away with the operation heretofore practiced of swaging and upsetting various portions of the same, and at the same time to produce not only an equally good article, but also to enable hand-made plates to be produced rapidly and of an equal quality with machine-made plates, thereby putting in the power of blacksmiths and other similar wagon-manufacturers economically to make and apply bolster-plates to wagons of their manufacture.

To enable others skilled in the art to make and use my invention, I will now describe it by reference to the accompanying drawings, in which—

Figures 1, 2, and 3 are views of the various parts of my improved plates. Figs. 4 and 5 are respectively longitudinal and transverse sections of the same when put together. Fig. 6 is a vertical sectional view showing the lower plate fitted on the bolster.

Like letters of reference indicate like parts in each.

The upper and lower plates, *a*, *b*, are preferably formed by rolling, with beads or flanges *a'* *b'* along their edges on one side, so as to adapt them to be fitted to the bolsters. Holes *a'* *b'* are then punched through the plates at the middle for the passage of the king-bolt.

In the hole *b'* of the lower plate I insert a short tube or sleeve, *c*, the lower end of which is provided with a flange, *c'*, or is flared out, or otherwise made with an enlargement or

bead upon the outside, the purpose of which is to secure it firmly in place between the lower bolster and the plate *b* when the latter is fastened onto the bolster. If desired, the top of the bolster may be recessed to receive the flanged end of the tube *c*. The tube *c* is of sufficient length to extend through the upper plate, *a*, and it is designed not only to afford support to the king-bolt, but also to take the strain of the upper plate, *a*, off of the king-bolt. The plates *a* *b* are provided with holes *a'* *b'* for the attachment-screws, in the usual way. The tube *c* may, if desired, be detachable from the plate *b* and sold separately as an article of merchandise, so that any person can purchase it and apply it to ordinary flat iron bolster-plates, thereby gaining all the advantages of machine-made swaged plates.

By my invention I effect a large saving in manufacture and avoid all danger of straining the metal, to which bolster-plates having upset and swaged portions are exposed.

What I claim as my invention, and desire to secure by Letters Patent, is—

1. The combination of the bolster-plates *a* *b*, the bolster *d*, and flanged tube *c*, the flange of which is secured between plate *b* and bolster *d*, substantially as and for the purposes specified.

2. The combination of the bolster-plates *a* *b*, having flanges *a'* *b'*, the bolster *d*, and the flanged tube *c*, extending through the plates, and the flange of which is supported by the bolster, substantially as and for the purposes specified.

In testimony whereof I have hereunto set my hand this 14th day of July, A. D. 1884.

RAPHAEL SERGEANT.
